UNITED STATES PATENT OFFICE

161,340

LIGHTING FIXTURE LOUVER

Raymond F. Hurley, Chicago, Ill.

Application January 31, 1950, Serial No. 7,603

Term of patent 14 years

(Cl. D48—23)

To all whom it may concern:

Be it known that I, Raymond F. Hurley, a citizen of the United States, residing at Chicago, county of Cook and State of Illinois have invented a new, original, and ornamental Design for a Lighting Fixture Louver, of which the following is a specification, reference being had to the accompanying drawing, forming a part thereof, in which:

Figure 1 is a bottom perspective view of a lighting fixture louver showing my new design;

Figure 2 is a bottom plan view;

Figure 3 is a top plan view;

Figure 4 is a side elevational view, and

Figure 5 is a cross sectional view taken along the line 5—5 of Figure 3.

I claim:

The ornamental design for a lighting fixture louver, as shown.

RAYMOND F. HURLEY.
